UNITED STATES PATENT OFFICE.

WILLIAM FESSENDEN BEASLEY, OF OXFORD, NORTH CAROLINA.

LOCK.

SPECIFICATION forming part of Letters Patent No. 439,624, dated November 4, 1890.

Application filed May 28, 1889. Serial No. 312,384. (Model.)

To all whom it may concern:

Be it known that I, WILLIAM FESSENDEN BEASLEY, a citizen of the United States, residing at Oxford, in the county of Granville and State of North Carolina, have invented 5 certain new and useful Improvements in Locks; and I do hereby declare the following to be a full, clear, and exact description of the invention, such as will enable others skilled in the art to which it appertains to 10 make and use the same.

My invention has for its object to provide means whereby a lock having a rotatable barrel and a register actuated thereby—such as 15 that described in the patent granted to Henry Clarke, September 30, 1879, and numbered 220,124—may be adapted to lock the lids of boxes, &c.; and for this object it consists in attaching a projection upon the rotatable 20 barrel having an arc-shaped flange thereon, which is adapted to engage a corresponding flange upon a fixed catch, as will be herein-after more fully described and claimed.

Referring to the accompanying drawings, in 25 which corresponding parts are designated by similar letters, Figure 1 is a sectional view of my invention applied to a box. Fig. 2 is a top view of the locking and registering mechanisms. Fig. 3 is a front end view of Fig. 2. Fig. 4 is a section on line $x-x$ of Fig. 2. Fig. 30 5 is a detail perspective view of the wheels H' , &c. Fig. 6 is a detail of the annular trough F .

The lid A' of the box A is provided with a 35 easing a , which contains the hereinafter-described mechanism, while a catch a' is formed in the body of the box to receive the projection b upon the collar b' on the barrel B of the lock. The catch a' and projection b have 40 arc-shaped flanges a^2 and b^2 , respectively, which, by engaging, prevent the opening of the box without first partially revolving the barrel, in which case the projection b takes the position shown in Fig. 3.

In order to prevent a backward rotation of 45 the barrel, it is provided on its rear end with shoulders C , having inclined forward faces c and square rear faces c' , which rear faces, if an attempt is made to turn the barrel back- 50 ward, strike against the inner ends of the outer pins D , (one of which is shown in Fig.

4, the others being immediately in the front and rear thereof, and therefore not shown,) contained in holes in the base-plate D^3 , and which are kept constantly forced against the 55 barrel by springs D' . The pins D also enter the holes c^2 in the barrel when in line therewith, and thus prevent the rotation thereof, either forward or backward, until forced out by the inner pins D^2 , contained in such holes, 60 and the key, as is common in the so-called "Yale lock," and which therefore needs no further description here.

Loosely mounted on the barrel B are disks E, E', E^2 , and E^3 , having alternate notches and 65 projections e' on their peripheries, while the successive numbers from 0 to 9, inclusive, are printed on such projections. A button E^4 is attached to each disk E, E', E^2 and a pin E^5 inserted between such disk and button. A 70 lug e^2 is also formed on the barrel and engages the recess f in the annular trough F , which is also mounted on the barrel, and caused to revolve therewith by means of the lug e^2 and recess f , while a pin f' is located 75 within the trough.

The post G , attached to the base-plate D^3 of the locking mechanism, is parallel to the barrel B , and carries thereon gear-wheels H , H', H^2 , and H^3 , each of which has a crown-gearing formed by studs h projecting from the sides thereof and a spur-gearing formed by a corresponding number of shoulders h' on the periphery. The studs h gear with the notches e of the disks E , &c., while the shoulders h' on the disks H, H', H^2 , and H^3 are struck by the pin f' in the annular trough F and the pins E^5 on the disks $E, E',$ and E^2 , respectively.

It will now be seen that if the box A be 90 locked and the numbers on the disks $E, E',$ &c., are read through the slot a^3 in the cover of the box that a rotation of the barrel B , which must be made in order to unlock the box, will cause the pin f' in the annular 95 trough F to strike one of the shoulders h' on the wheel H , thus moving the latter one tooth forward, which motion will be transferred to the disk E by means of a stud h and a recess e , the said disk being moved forward the distance of one projection e' , and thus the succeeding number will come under the slot a^3 , 100

and it will be seen in comparing the previous reading of the register with the present that the box has been opened. In case the disk E is already recording its highest number (9) 5 and the barrel is turned the pin E⁵ on the said disk strikes a shoulder h' of the wheel H', which is thereby moved, transmitting the motion to the succeeding disk E' by means of studs h and recesses e. It is thus evident 10 that on each completed revolution of one of the disks E, E', or E³ the succeeding disk is moved the space of one projection, carrying a proportionally-larger number under the slit a³; and that the first wheel E represents 15 units, the second E' tens, the third E² hundreds, and the fourth E³ thousands, and that by the above-mentioned system of four wheels I can register nine thousand nine hundred and ninety-nine revolutions of the barrel B. 20 The shoulders C on the barrel prevent, as before stated, the backward motion thereof, which would otherwise destroy the accuracy of the registration.

Having now described my invention, what I

claim, and desire to secure by Letters Patent, 25 is—

1. The combination, in a lock, of a rotary barrel, a projection on one side thereof having an arc-shaped flange thereon, a catch, also having an arc-shaped flange, engaging the flange 30 upon the projection, and a register actuated by the rotation of the barrel, as described.

2. The combination, in a lock, of a rotary barrel having shoulders and a projection formed thereon, an arc-shaped flange on the said projection, a catch, also having an arc-shaped flange, engaging the flange upon the projection, a register actuated by the rotation of the barrel, and a spring-catch engaging the 35 said shoulder upon the barrel against backward rotation, as described.

In testimony whereof I have affixed my signature in presence of two witnesses.

WILLIAM FESSENDEN BEASLEY.
